Primary Examiner — Cynthia Underwood(74) *Attorney, Agent, or Firm* — Additon, Higgins & Pendleton, P.A.(57) **CLAIM**

The ornamental design for an electronic device enclosure, as shown and described.

DESCRIPTION

FIG. 1 is a perspective view of the electronic device enclosure disclosed herein;

FIG. 2 is a perspective view of the electronic device enclosure of FIG. 1 with a handle in an upright position;

FIG. 3 is a rear view of the electronic device enclosure of FIG. 1;

FIG. 4 is a front view of the electronic device enclosure of FIG. 1;

FIG. 5 is a right side view of the electronic device enclosure of FIG. 1;

FIG. 6 is a left side view of the electronic device enclosure of FIG. 1;

FIG. 7 is a top plan view of the electronic device enclosure of FIG. 1; and,

FIG. 8 is a bottom plan view of the electronic device enclosure of FIG. 1.

The broken lines in the drawings depict environmental subject matter/or parts of the electronic device enclosure and form no part of the claimed design.
